(57) **CLAIM**

The ornamental design for a splatter guard, as shown and described.

DESCRIPTION

FIG. 1 is a perspective view of a splatter guard showing our design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top view thereof;

FIG. 7 is a bottom view thereof; and,

FIG. 8 is a perspective view of the splatter guard in a partially folded use condition.

The even length broken lines depict portions of the splatter guard that form no part of the claimed design. The uneven length broken lines adjacent to the shaded regions define the bounds of the claimed design and form no part thereof. The remaining uneven length broken lines represent environment and form no part of the claimed design.
